UNITED STATES PATENT OFFICE

BENJAMIN W. WOODWARD, OF BROOKLYN, NEW YORK, ASSIGNOR TO WALTER HOWEY,
OF NEW YORK, N. Y.

MULTIPLE PLATE PHOTO ELECTRIC TUBE

Application filed March 31, 1930. Serial No. 440,333.

My invention relates to improvements in multiple plate photo electric tubes and it more especially relates to the features pointed out in the annexed claims.

5 The purpose of my invention is to provide a light sensitive tube having a plurality of separate light sensitive surfaces each adapted to vary the current of electricity in accordance with differences in illumination to 10 which each surface is subjected; that provides suitable supports for the separate plates and positions the plates with respect to each other so as to cause their adjacent edges to project past each other; that encloses the 15 elements in a vacuum tube provided with a conventional base and fixed projecting terminals; and that is also provided with an anode which cooperates with the cathode surfaces.

20 With these and other ends in view, I illustrate in the accompanying drawing such instances of adaptation as will disclose the broad underlying features without limiting myself to the specific details shown thereon 25 and described herein.

Figure 1 is a front elevation of a tube.

Fig. 2 is a side elevation.

Fig. 3 is a bottom elevation of the usual five prong terminal.

30 Fig. 4 is a modified side view of Fig. 2.

In practicing my invention I may use whatever alternatives or equivalents in structure that varying conditions may demand without departing from the broad spirit of 35 the invention.

On the insulating base 1, an evacuated glass tube 2 is secured and within it the anode element 3 is supported and a group of cathode surfaces 4 are positioned, one above the 40 other, in off-set relation, as shown in Fig. 2; or in staggered relation so positioned in respect of each other that the adjacent edges of the plates overlap but do not touch each other. They are supported in any desired 45 manner by the conducting leads 5. These leads are insulated from each other and are connected with their respective pins 6.

This form of vacuum tube light sensitive tube is specially adaptable for multiple scanning and when so used the separate plates

4 are successively brought into circuit by any desired form of commutator and slip rings (not shown). The provision of a group of separate light sensitive surfaces insulated from each other affords a ready means for 55 selective scanning, each scanning path corresponding to one of the plates, thus four adjacent paths may be scanned in one revolution of a carrier on which a subject is supported. This arrangement increases the 60 scanning rate four times over what it would be with a single cathode element.

The tube may be used in connection with any desired current input to an amplifying system, the output of which may be used for 65 various purposes. The special adaptations of the tube are not specifically shown in this application as their description is not necessary to an understanding of the structure of my multiple plate photo electric tube.

What I claim is:

1. A light sensitive tube comprising an evacuated tube, an insulated supporting base therefor, a plurality of cathode plates separately supported and spaced apart from each 75 other with their adjacent edges overlapping, an anode element in operative relation to the plates, and suitable attaching prongs secured to the insulated base one for each separate plate and one for the anode element. 80

2. A light sensitive tube comprising an evacuated tube attached to an insulated base, a plurality of light sensitive plates positioned adjacent each other with their meeting edges in overlapping and spaced apart relation, 85 separate conducting supports for each plate, an anode element in spaced apart relation and extending across all of the plates, and corresponding terminals projecting from the insulating base. 90

3. An evacuated tube comprising an anode element, a plurality of adjacently positioned overlapping cathode light sensitive plates positioned in operative relation to the anode element, and suitable insulated supports for 95 each.

4. A light sensitive device comprising a plurality of light sensitive cathodes positioned adjacent with overlapping edges and in insulated relation to each other, an anode 100

suitably supported in relation common to all the cathodes, and separate external electrical connections for each of said cathodes and the anode.

5 5. A light sensitive device comprising a plurality of light sensitive unitary cathodes having overlapping edges each cathode being positioned adjacent to and in cooperation with a single anode that is common to all of the cathodes, means for supporting the cathodes and anodes in spaced apart relation so that light from a single source may reach all of the cathodes, and means for connecting each element separately to related external

15 circuits.

6. A light sensitive device comprising a plurality of separate cathodes in spaced apart and insulated relation to each other having their adjacent edges overlapping, a common anode in cooperation with each cathode, a tube for the anode and cathode elements, a separate electrical connection for each cathode leading from the tube and insulated from the others, and a separate electrical connection for the anode also being brought out from the tube and insulated from the cathode connections.

In testimony whereof I affix my signature.

BENJAMIN W. WOODWARD.
